UNITED STATES PATENT OFFICE.

GEORGE R. HANKS AND STANLEY APGAR, OF HIGH BRIDGE, NEW JERSEY; ALFRED R. BENCH, OF EASTON, AND GEORGE L. BIDWELL, OF RIEGELSVILLE, PENNSYLVANIA, ASSIGNORS TO TAYLOR-WHARTON IRON AND STEEL COMPANY, OF HIGH BRIDGE, NEW JERSEY, A CORPORATION OF NEW JERSEY.

INTEGRAL BEATER ROLL.

Application filed March 2, 1923. Serial No. 622,384.

To all whom it may concern:

Be it known that we, GEORGE R. HANKS, STANLEY APGAR, ALFRED R. BENCH, and GEORGE L. BIDWELL, citizens of the United States, residing, respectively, the said GEORGE R. HANKS and STANLEY APGAR at High Bridge, in the county of Hunterdon and State of New Jersey; the said ALFRED R. BENCH at Easton, in the county of Northampton and State of Pennsylvania; and the said GEORGE L. BIDWELL at Riegelsville, in the county of Bucks and State of Pennsylvania, have jointly invented a certain new and useful Integral Beater Roll, of which the following is a specification.

It has already been proposed to construct beater rolls with integral knives formed of manganese steel on account of its shock and wear resistive properties. A beater roll of this type is disclosed in Letters Patent, No. 1,362,219, granted December 14, 1920, to George L. Bidwell; and the integral construction is rapidly superseding beater rolls of the wood filled type.

We propose to construct a beater roll in the form of a single casting of manganese steel which, except for the headers or end closures, shall be complete and ready for mounting on the usual shaft of a Hollander engine.

Manganese steel offers serious foundry and heat treatment problems and these have been carefully considered and overcome in the experiments leading up to our invention.

The solid or integral construction to be hereinafter more particularly described, insures uniform heat treatment and hence longer life of the beater roll; it eliminates joints and their complemental fastenings and the necessity of filling the joints to exclude pulp and water from the interior of the roll; in a word, it makes for economy as well in the manufacture and mounting of the roll as in the operation thereof.

One embodiment of our invention is illustrated in the accompanying drawing, forming a part hereof, wherein—

Figure 1 is a longitudinal sectional view of a solid or integrally cast beater roll.

Fig. 2 is a cross sectional view of the same; and

Fig. 3 is a detail perspective view.

According to our invention a beater roll exclusive of end plates, but inclusive of the knife carrying cylinder or roll, the spiders 55 and the hubs or shaft receiving elements, is formed of a single casting, preferably of manganese steel.

The knife carrying cylinder 5 is formed with a pair of spiders 6 terminating in 60 sleeve-like extensions constituting hub elements 7 for the reception of the usual shaft. Each of the hub elements is equipped with one or more key-seats 8 whereby it may be locked to the shaft, and diametrically opposite the seat or seats with counterbalance provision 9.

The spiders 6 have points of contact as by spaced integers 10 between the hub elements. The integers 10 constitute strengthening 70 provisions and also facilitate the flow of metal in casting.

The cylinder 5 is reinforced by radial ribs 11 and by longitudinal ribs 12. The cylinder and the spiders are additionally reinforced by radially disposed webs 13. The latter also constitute abutments for the end closures 14, which may or may not have the usual bangers 15. The end closures 14 are substantially ground seated as at 16 and are so retained by bolts or other suitable fastenings 17 engaging the spiders. This arrangement together with the absence of joints in the cylinder makes for a fluid tight roll.

Having described our invention, we claim:

1. A beater roll embodying a hollow cylinder with integral knives and with integral radial supports formed with shaft openings.

2. A beater roll embodying a hollow cylinder with integral knives, means for centering the cylinder, and ground seated end closures for the cylinder.

3. A beater roll embodying a hollow cylinder with integral knives, means for centering it including a spider at each end of the cylinder and formed integral therewith, and stress distributing provisions symmetrically formed over that area of the cylinder intermediate the spiders.

4. A beater roll consisting of a heat-treated manganese steel casting formed as an open construction which is inclusive of an intact knife-carrying periphery and

- spaced radial supports formed with shaft openings.
5. A beater roll embodying a hollow cylindrical casting with integral knives, means for centering it, and end closures for the cylinder.
6. A beater roll embodying a hollow cylinder with integral knives and with integral radial supports having shaft openings, and web connections intermediate said supports and the cylinder.
7. A beater roll embodying a hollow cylinder with integral knives and with integral radial supports or centers, and ribs ranging longitudinally and radially of the cylinder and having points of intersection.
8. A beater roll embodying a hollow cylinder with integral knives and with integral centers joined by the bars, and means for bracing that portion of the cylinder intermediate the centers.
9. A beater roll embodying a hollow cylinder with integral knives and with integral radial supports or centers, and webs between the supports and cylinder and constituting 25 abutments for end closures.
10. A beater roll embodying a hollow cylinder with integral knives and with an integral spider at each end thereof, the hubs of the spiders being integrally united at 30 spaced intervals.
11. A beater roll embodying an open cylinder with integral knives and with integral centers, and means for sealing the ends of the cylinder.
12. A beater roll embodying a knife carrying cylinder of hollow construction formed with integral centers and with spaced integers connecting the centers.
13. A beater roll embodying knives, knife-supporting body, spiders, and hubs, all of said elements being cast integral.

In testimony whereof, we affix our signatures.

GEORGE R. HANKS.
STANLEY APGAR.
ALFRED R. BENCH.
GEO. L. BIDWELL.
